 Mills Company, Rothschild, Wis., a corpora-
 tion of Wisconsin

Application December 16, 1940, Serial No. 370,416

1 Claim. (Cl. 312—62)

This invention relates to a dispensing cabinet for a stack of sheets such as waxed paper, napkins, and the like.

One of the objects of the invention is to provide a dispenser for suitably retaining a stack of sheets, and to permit withdrawal of one sheet at a time therefrom.

A further object of the invention is to provide a dispenser which will permit removal of only one sheet at a time while retaining the remaining stack of sheets within the dispenser and protecting the same against contamination by dust or other foreign substances.

A further object of the invention is to provide a stack of sheets which are suitably notched at certain portions thereof for facilitating retention within a suitable dispenser and to permit withdrawal of only one sheet at a time therefrom.

A further object of the invention is to provide a dispensing cabinet so constructed as to suitably retain a stack of notched sheets whereby a single sheet at a time can be removed from the dispenser without disturbing the remaining sheets of the stack.

Other and further objects of the invention will be apparent from the following specification and annexed drawings wherein

Figure 1 is a perspective view of the dispenser illustrating an embodiment of the invention,

Figure 2 is a side elevational view of the dispenser,

Figure 3 is a plan view of the dispenser,

Figure 4 is a sectional view taken on lines 4—4 of Figure 3, and

Figure 5 is an enlarged fragmental sectional view taken on lines 5—5 of Figure 3.

Referring to the drawings wherein like numerals refer to like parts, the dispenser constructed in accordance with the present invention consists of a bottom 10, opposed end walls 14, and opposed side walls 20. Guide slots 16 are provided in the end walls 14 extending vertically and preferably for the full height of the end walls as shown in Figure 1. The upper edge portions of the end walls may be bent outwardly to provide flange portions 15 for convenience of handling the dispenser as well as for serving as a stop portion for lugs 26 integral with cover members 25 and 27 which are slidably engaged in the slots 16 for guiding the cover members 25 and 27 at all positions thereof within the dispenser.

The cover members 25 and 27 are adapted to rest freely under the influence of gravity upon

the top of the stack of sheets A. In order to further assist in guiding the covers 25 and 27 the side walls 20 are provided with a pair of opposed guide flange members 22 and 23 which may be struck out from the side walls as illustrated in Figures 1 and 5. The portions of the covers adjacent these vertical guide flange members are cut out as indicated by numeral 35 in Figure 3 for slidable engagement therewith. The cover members 25 and 27 will thus be guided at all times by the lugs 26 and the vertical flange members 22 and 23. The covers normally rest in horizontal position on the stack simply by force of gravity and automatically adjust themselves to the height of the stack within the dispenser as the sheets are removed therefrom.

The opposed free edges 25—a and 27—a of the covers are preferably cut out in a curved contour as indicated in Figures 1 and 3 and the free edges are spaced apart a suitable distance so as to expose the uppermost sheet in the stack A. In order to facilitate ready grasping of the uppermost sheet the bottom 10 of the dispenser is provided with an elevated ridge 12 having an inverted V-shaped contour illustrated in Figures 3 and 4. This elevated portion serves to bend or arch upwardly the stack of sheets resting thereon whereby the uppermost sheet in the stack will be bent outwardly beyond the free edges 25—a and 27—a of the covers as illustrated in Figures 1 and 4 so that the sheet can be readily grasped by the fingers and readily removed from the dispenser. The sheets are preferably provided with a pair of opposed cut-out V-shaped notches 30 which are adapted to engage the vertical guide flanges 22 and 23 provided in the side walls of the dispenser. By this means the stack of sheets will be more securely retained within the dispenser and when the uppermost sheet is removed the adjacent sheets below will not tend to be removed because the notches 30 will be in engagement with the flange members 22 and 23 and the body of the sheet is held down by the weight of the covers 25 and 27. The dispenser may be also provided with suitable leg portions 11 for supporting the dispenser upon a table, counter, or any other surface on which it may be placed.

The dispenser is advantageously constructed from sheet metal or any other suitable material. When the stack of sheets within the dispenser has been completely used up the covers 25 and 27 can be hinged outwardly, the lugs 26 permitting the covers to be hinged upwardly and outwardly of the dispenser. A new stack

of sheets is then placed within the dispenser and the covers are then replaced in normal position so as to rest upon the stack in the position illustrated in Figure 1. The dispenser is then ready for immediate use. Any suitable sheet material may be utilized in this dispenser such as waxed paper, paper napkins, and the like. The dispenser is particularly adapted for use with very thin waxed tissue as the sheets may be withdrawn one at a time without withdrawing adjacent sheets. The dispenser also protects the stack of sheets from being contaminated by dust or dirt as only the uppermost sheet is exposed within a very small area between the opposed free edges of the covers. The dispenser requires no springs or other mechanism which might get out of order. It is very simple in construction and efficient in operation.

It is obvious that numerous changes and modifications may be made in the construction, and 20 that all such variations and modifications are intended to be included within the scope of the following claim.

We claim:

A dispensing cabinet for a stack of sheets having a bottom, opposed side walls and end walls, vertically extending guide slots in the end walls, 5 cover members having lug members receivable and slideable in said slots, said cover members being adapted to rest freely under the influence of gravity on said stack of sheets, the free edges of said cover members being spaced apart to expose the uppermost sheet in said stack, a pair of opposed vertically extending guide flange members in the said side walls, each of said cover members being cut away adjacent said guide flange members for slideable engagement therewith, and said bottom having a portion thereof elevated and aligned between the opposed free edges of said cover members, whereby the stack 10 of sheets is curved upwardly for permitting ready grasping of the uppermost sheet.
